RAILWAY BRAKE MECHANISM

Filed May 12, 1927

FIG. 1.

FIG. 2.

BY

INVENTOR
LOUIS D. GREGG
ATTORNEYS

UNITED STATES PATENT OFFICE

LOUIS D. GREGG, OF HACKENSACK, NEW JERSEY, ASSIGNOR TO THE GREGG COMPANY, LTD., OF HACKENSACK, NEW JERSEY, A CORPORATION OF NEW YORK

RAILWAY BRAKE MECHANISM

Application filed May 12, 1927. Serial No. 190,733.

This invention relates to improvements in brake mechanism for railway cars and the like.

It is an object of this invention to provide an improved device of the class described which will equalize the applied pressure to the respective brake shoes of the railway car wheels when the brake applying levers are operated.

10 It is a further object of this invention to provide a brake equalizer for railway vehicles that will be more efficient in use, more rugged in construction, and less expensive in cost of manufacture.

15 It is a further object of this invention to provide an improved brake rigging for railway cars of the single truck type in which the brake parts are entirely out of the way of any obstruction that may come on the tracks.

20 It is a still further object of this invention to provide an equalized brake rigging in which the connecting link between the brake beams is entirely above the center of the wheel axles.

25 It is another object of this invention to provide a brake rigging that will equalize the pressure between the various wheels and be operated by a single arm operating handle extending from either side of the car.

30 Further objects and advantages will appear from the following detailed description of one form of embodiment exemplifying my invention and, in which:

Fig. 1 is a side elevation of a part of the 35 truck.

Fig. 2 is an end elevation of the car truck and

Fig. 3 is a detail of the brake rigging.

In certain industries, such as that of sugar 40 growing, small cars which are frequently hand-operated, are used and it is necessary that they be equipped with suitable, efficient and economical brakes of such rugged construction that they will withstand hard serv-

45 ice conditions and, further, they must be of such character that one man may be able to obtain the maximum braking power possibly obtainable, and the parts should be as high as possible above the track to prevent damage 50 from obstructions on the track in derailment,

which are frequent when the cars are used on portable or temporary tracks.

The brake rigging shown therefore has been found to be of this character and is applied to a cane or other small car 10 equipped with wheels 11 which are to be braked by brake shoes 12 at the ends of respective brake beams 13, running transversely of the car and suspended from the car by pivoted links 27.

55 As shown in Fig. 1, the dead lever 14 is pivotally attached at its top to the dead brake lever bracket 15 and at the bottom by means of the adjustable clevis 16 shown in Fig. 3, to the rear brake beam 13.

60 Intermediate of these two points of attachment, a connecting link 17 is also pivotally attached to the dead lever 14 and continues forwardly above the car wheel axles to the floating equalizing lever 18, which, at the lower end, is similarly fastened to the forward 65 brake beam 13 in the same manner as the dead lever was attached to its beam.

70 The floating equalizing lever 18 is slidably supported on an angle-shaped bracket 19 by means of a roller bearing 20, placed between 75 the sides 18 and 18a of the live lever, which will allow certain slight movement without undue friction.

75 The uppermost end of the live lever is connected to a bell crank 21 through the intermediate horizontal link 22, and a link 23 from the other arm of the bell crank which is centrally pivoted to the frame of the car at 21a extends upwardly to an operating handle 24, pivoted to the car at 25, and whose extremities extend outwardly beyond the sides 80 of the car.

85 The operating arm 24 has an angular detent 24a thereon cooperating with a notched bracket 26 on the car end so that the bracket 90 may retain the operating handle 24 in any desired position and thus maintain any degree of braking power desired.

95 The operation of this device is as follows: The operator, desiring to apply the brakes, will grasp either end of the handle 24, depending upon the side of the car that he is stationed, and by forcing downwardly if on the detent side or upwardly on the other side, he will exert an upward force on the link 23, 100

which is changed by the bell crank to a horizontal force acting on the live lever 18 to pull it toward the right of Fig. 2. Immediately the right hand brake beam 13 will actuate its brake shoes against the respective wheels and then the reaction will cause the left hand brake beam to also move its brake shoes against their respective wheels. Cross equalization is accomplished by relative looseness of the brake beam pivots and clevis 16 and to the slight resiliency in the angular brake beams 13.

It will be obvious from the above description that inasmuch as the brake beams are of angular construction and, as the live and dead levers are supported intermediate of the car frame, but one connecting link is necessary, which, being above the car axles, is not subject to accident from obstacles on the track, and due to the floating lever 18, a very simple, rugged and efficient equalizing means is provided which may be manufactured at a small cost.

While I have illustrated one form of embodiment of the device, I am aware that other modifications within the spirit of this invention, may be made and I, therefore, desire protection on the broad interpretation of the spirit and scope of this application and of the appended claims.

What I claim as my invention is:

1. In a brake mechanism of the class described, the combination of brake levers suspended from a car frame, brake beams attached to the end of said levers and respective brake shoes, one of said brake levers being connected at its top to an actuating link, and being connected in substantially its center to a connecting link operating the other brake lever, and intermediate of these two positions suspended from the car frame for pivotal and limited longitudinal movement.

2. In combination with a railway car and its wheels of the class described, brake rigging comprising a brake lever pivoted to the car frame and attached to a brake beam and its respective brake shoes, a second brake lever also attached to a brake beam having brake shoes, the second lever being laterally and pivotally movable relative to the car frame, a single link connecting said levers midway between the ends thereof for simultaneous movement, and an operating arm actuating said brake shoes adapted to be positively positioned in any desired place.

3. In combination with a railway car and its wheels of the class described, brake rigging comprising a brake lever pivoted to the car frame and attached to a brake beam having two brake shoes, a second brake lever also attached to a brake beam having two brake shoes, the second lever being laterally and pivotally movable relative to the car frame, a single link connecting said levers between the ends thereof and above the car

axles for simultaneous movement, and an operating arm actuating said brake shoes adapted to be positively positioned in any desired place.

4. In a brake mechanism of the class described, the combination of a double bar floating lever slidably and pivotally supported from the frame of a railway car, and having its lower extremity secured to a brake beam with suitable shoes attached; and a supplementary brake lever pivotally connected to the car frame and to the first lever by means of a rigid connecting rod; a brake beam and shoes attached to said supplementary rod, and control means to manipulate the whole by a suitable governing lever controlled from either side of the car.

5. In a brake mechanism for a car frame, live and dead brake levers suspended from the frame, one of said levers having a movable pivot on the frame by which it is suspended, brake beams attached to the ends of the respective brake levers, brake shoes supported by the end of the brake beams and means to actuate the said levers to equalize the brake shoe pressure, comprising an intermediate connecting link and an actuating link.

6. In a brake mechanism for railway cars, the combination with a car frame having wheels thereon, of live and dead brake levers suspended from the car frame, one of said levers being suspended from the frame by a sliding pivot, brake beams attached to the ends of the brake levers, brake shoes supported by the beams, said brake levers being connected medially by means of a single link extending therebetween above the car axles, the other lever being secured to the car frame by the fixed pivot and a double arm operating handle for actuating the brakes connected to the live lever.

In testimony whereof I have affixed my signature to this specification.

LOUIS D. GREGG. 110
